Primary Examiner — Mark A Goodwin(74) *Attorney, Agent, or Firm* — John Anderton(57) **CLAIM**

The ornamental design for wear part for earth working equipment, as shown and described.

DESCRIPTION

FIG. 1 is a perspective view of a wear part for earth working equipment in accordance with the present invention.

FIG. 2 is a cross section view taken along line 2-2 of FIG. 1.

FIG. 3 is a cross section view taken along line 3-3 of FIG. 1; and,

FIG. 4 is another perspective view of FIG. 1.
The broken lines in the drawings depict unclaimed environmental subject matter and form no part of the claimed design. The cross hatching depicts an interior portion of the wear part and forms no part of the claimed design.**1 Claim, 3 Drawing Sheets**| (56)	References Cited
